US00D818599S

(12) **United States Design Patent** (10) Patent No.: **US D818,599 S**
(45) Date of Patent: **** May 22, 2018**

(54) **ACUPRESSURE DEVICE**

(71) Applicant: **BR CONSULTING, INC.**, Sedona, AZ (US)

(72) Inventor: **Seung Hun Lee**, Sedona, AZ (US)

(73) Assignee: **BR CONSULTING, INC.**, Sedona, AZ (US)

(**) Term: **15 Years**

(21) Appl. No.: **29/572,821**

(22) Filed: **Jul. 30, 2016**

(30) **Foreign Application Priority Data**

Mar. 17, 2016 (KR) 30-2016-0012520

(51) LOC (11) Cl. **28-03**

(52) U.S. Cl.

USPC **D24/214**

(58) **Field of Classification Search**

(57) **CLAIM**

The ornamental design for acupressure device, as shown.

DESCRIPTION

FIG. 1 is a perspective view;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets

FIG. 1

FIG. 2

FIG. 3

FIG. 4

FIG. 5

FIG. 6

FIG. 7
